ROTARY BOOK RACK

Robert Lieberman, Detroit, Mich.

Application January 7, 1957, Serial No. 44,415

Term of patent 7 years

(Cl. D33—2)

Fig. 1 is a front perspective view of a rotary book rack, showing my new design; and

Fig. 2 is a side elevational view thereof.

I claim:

The ornamental design for a rotary book rack, as shown.
